CLAIM

The ornamental design for a panel, as shown and described.

DESCRIPTION

The patent or application file contains at least one drawing
executed in color. Copies of this patent or patent application
publication with color drawing(s) will be provided by the
Office upon request and payment of the necessary fee.

FIG. 1 is a front view of a panel, according to a new design;
FIG. 2 is a rear view thereof; and,
FIG. 3 is a right side view thereof.

The broken lines and areas within them depict features of the
panel that form no part of the claimed design.
